AUXILIARY IGNITION SYSTEM FOR INTERNAL-COMBUSTION ENGINES

Carl E. Maier, Chicago, Ill., assignor to Blackstone Manufacturing Co., Inc., Chicago, Ill., a corporation of Illinois

Application November 10, 1941, Serial No. 418,460

1 Claim. (Cl. 200—42)

This invention relates to auxiliary ignition systems for internal combustion engines.

Generally, ignition systems for internal combustion engines are highly efficient and reliable in service. However, with prolonged usage the liability of failure or breakdown of the system is increased. The contact surfaces of the breaker points become pitted and reduce the efficiency of the engine. Both the induction coil and condenser may fail, correspondingly causing the system to fail and necessitating a curtailment in the operation of the engine pending replacement or repair of the defective parts.

Having in mind the foregoing limitations of present ignition systems, it is, therefore, the object of this invention to provide auxiliary means applicable to existing systems for efficiently continuing the operation of the engine after failure of one or more of the parts in the system.

A further object of this invention is the provision of switching means whereby the auxiliary ignition system may be cut in upon failure of the originally installed system.

With the foregoing and other objects in view, the invention consists of the novel construction, combination and arrangement of parts, as hereinafter more specifically described and illustrated in the accompanying drawings wherein is shown a device in accordance with this invention, but it is to be understood that changes, variations and modifications can be resorted to which fall within the scope of the appended claim.

In the drawings wherein like reference characters denote corresponding parts through the several views:

Fig. 1 is a diagrammatic view showing a conventional ignition system for internal combustion engine with the auxiliary system applied thereto and operating in conjunction therewith.

Fig. 2 is a side elevational view of a complete switching unit embodied in my invention.

Fig. 3 is an end elevational view looking in the direction of the arrows 3—3 of Fig. 2.

Fig. 4 is a similar view looking in the direction of the arrows 4—4 of Figure 2.

Fig. 5 is a longitudinal cross sectional view taken on line 5—5 of Fig. 4.

Fig. 6 is a cross sectional view on line 6—6 of Fig. 5.

Fig. 7 is a similar view taken on line 7—7 of Fig. 5.

Fig. 8 is an elevational view of a detail looking in the direction of arrows 8—8 of Fig. 5.

Fig. 9 is a cross sectional view taken on line 9—9 of Fig. 5.

Referring to the drawings Fig. 1 diagrammatically illustrates a conventional ignition system comprising a battery 15 connected to an ignition switch 16 in circuit with the primary winding 18 of an induction coil 19 which is connected to a circuit breaker 20 actuated by a cam 31. The primary winding is wound around an iron core as shown. The shaft of the said cam carries the distributor rotor 22 which in conventional systems is usually connected with the secondary winding 24 of the coil 19 and which cooperates with the terminals 25 connected to the spark plugs 26. The condenser usually connected across the breaker points 20 is indicated by the numeral 28.

The auxiliary system which constitutes the subject matter of this invention includes a switch indicated generally by the numeral 30, an induction coil 31, the primary winding 33 of which operates as an electromagnet circuit interrupter to produce a flow of high tension current from the secondary winding 34 delivered in proper sequence to the spark plugs 26 by the rotor 22.

In the particular form of auxiliary coil 31 herein disclosed, the primary winding 33 is provided with an iron core 36 which actuates the vibrating armature 37 to interrupt the current through the primary winding 33 in the well known manner. A condenser 38 is connected across the contact point 39 and the contact point on the armature 37.

The switch 30 hereinbefore referred to comprises a casing 41 formed of plastic or other suitable insulating material and provided with a plurality of apertured bosses 42, 43 and 44 arranged to accommodate metal contact elements 45, 46 and 47 respectively. The said apertured bosses provide sockets for the reception of wires hereinafter to be described. Another pair of bosses 49 and 50 are provided in the lower portion of the casing 41 and are arranged to receive contact posts 52 and 53 respectively. Associated with the casing 41 is a metal section 54 having an extended neck portion 55 housing a conventional cylinder lock 59. Nuts 56 and 57 in threaded engagement with the neck 55 serve to secure the switch 30 to a dashboard 58 as illustrated.

The cylinder 59 is provided at one end with a squared recess 61 to receive a stem 62 having a correspondingly shaped end portion. An insulating washer 64 having a central square aperture is mounted on the squared end of the stem 62 and is arranged to be rotated simultaneously therewith. A metal disc 66 provided with two embossed portions 68 is mounted on the washer

64 as by lugs. The central aperture of the disc 66 is sufficiently enlarged to accommodate the stem 62 without contact therewith.

Adjacent to the disc 66 and coaxial therewith is an insulating circular member 70 provided with diametrically opposed bosses 71. The said bosses have apertures to receive screws 73, 73a which are retained therein by nuts or inserts 74 received in counter sunk holes. The circular member 70 is suitably supported by a disc member 76 provided with apertures for accommodating the bosses 71. A central aperture is also provided in the member 76 to accommodate the stem 62 without contacting same.

The embossed portions 68 of the disc 66 are arranged to register with the nuts 74, when the stem 62 is selectively rotated as by the key 75 in the cylinder, and to serve as an electrical conductor therebetween. A spring 77 serves to urge the disc 66 against the nuts or inserts 74 particularly when the embossed portions 68 are in registering alignment therewith. The contact posts 52 and 53 are connected to screws 73 and 73a respectively by wires 79 and 80.

Mounted on the end of the stem 62 for movement therewith is an insulated member 82 provided with a spring member 83 riveted over a metal projection 84 and carrying a contact element 85. The said contact element is maintained in constant engagement with contact element 45 while the stem 62 may be selectively rotated to move the projection 84 into engagement with either of the contact elements 46 or 47 as desired.

The device may consist of two separate units, the switch 30 and coil 31, or the same may be combined in a single casing. In either case the device is adapted for mounting on an instrument panel or the like and is readily connected in service simply by detaching the high tension wire 87 normally connected to the rotor 22 and plugging the same into the socket 43. The lead 88 from the secondary winding 34 of the coil 31 is similarly plugged into the socket 44. The rotor 22 is connected by wiring 89 to the socket 42 of switch 30. Contact post 53 is connected by wiring 90 to the positive terminal of the battery 15 and contact post 52 is connected by wiring 91 to contact point 39.

The switch 30 may be actuated to cut in the auxiliary system in service, or to cut out the same and restore the original connections of the ignition system. Since the members 66 and 82 are both fixedly mounted on the stem 62, it is readily seen that by turning the key 75, one quarter of a turn, clockwise or counterclockwise, as the case may be, the original ignition system may be cut out and the auxiliary system cut in service.

In the position illustrated in Fig. 1, the switch 30 is shown as cutting in the auxiliary ignition system and cutting out the original system. The current flows from the battery 15, through the wire 90, member 66, wire 91, vibrating armature 37 and primary winding 33 where it is converted to high tension current which then passes through wire 88, member 83, wire 89 to rotor 22 of the distributor where it is delivered in proper sequence to the spark plugs 26.

When it is desired to cut out the auxiliary system and to revert to the original ignition system, the switch 30 is actuated to the left so that the member 83 engages the contact element 46, and embossings 68 of member 66 are out of engagement with the nuts 74, 74 electrically connected to contact posts 52 and 53. In this case the current follows the conventional ignition flowing from the secondary winding 24 through wire 87, contact element 46, member 83 and wire 89 to distributor rotor 22 where it is delivered in proper sequence to the spark plugs 26.

From the foregoing, it will thus be seen that the invention provides a complete auxiliary ignition system which may be readily cut into service upon failure of the original system.

It is to be understood that the form of my invention, herewith shown and described, is to be taken as a preferred example of the same, and that various changes in the shape, size and arrangement of parts may be resorted to, without departing from the spirit of my invention or the scope of the appended claim.

I claim:

35 A switch comprising an insulating casing having an extended neck portion housing a cylinder lock, a stem mounted coaxially with said lock and rotatable therewith, an insulating disc mounted on one end of said stem and rotatable therewith, said insulating disc having a pair of integral contact elements mounted thereon, an insulating member mounted in said casing through which said stem merely extends, said insulating member carrying a pair of opposed contact members arranged to register with said contact elements when said stem is selectively rotated as by a key in said lock, spring means for urging said contact elements and said contact members in engagement, and a contact element insulatably mounted on the other end of said stem and rotatable therewith, said contact element arranged to selectively bridge a contact terminal mounted in said casing coaxially with said stem and one of two contacts mounted radially thereof.

CARL E. MAIER.
